(57) **CLAIM**

The ornamental design for a wireless charging dock, as shown and described.

DESCRIPTION

FIG. 1 is a front elevational view of a wireless charging dock showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, left, and top perspective view thereof; and,

FIG. 8 is a rear, right, and bottom perspective view thereof.

The broken (dashed) lines show portions of the wireless charging dock that form no part of the claimed design.
